(57) **CLAIM**

The ornamental design for a re-bar for attachment to wire reinforcing elements for structural walls, including stucco, plaster, brick and concrete walls, and the like to improve reinforcement thereto, as shown and described.

DESCRIPTION

FIG. 1 is a perspective view of a re-bar for attachment to wire reinforcing elements for structural walls, including stucco, plaster, brick and concrete walls, and the like to improve reinforcement thereto, showing our design;

FIG. 2 is a top plan view thereof;

FIG. 3 is a bottom plan view thereof;

FIG. 4 is a side view thereof;

FIG. 5 is a front view thereof; and,

FIG. 6 is a rear view thereof.
